UNITED STATES PATENT OFFICE

FRANCIS N. WOODMAN, OF CLINTON, MASSACHUSETTS, ASSIGNOR TO WICKWIRE
SPENCER STEEL COMPANY, OF NEW YORK, N. Y., A CORPORATION OF DELAWARE

CONVEYER BELT WITH REINFORCED RAISED EDGES

Application filed March 18, 1929. Serial No. 347,749.

This invention relates to a belt formed of interlaced or interwoven wire members and designed for use in the transportation for varied articles or materials.

5 It is the object of my invention to provide integral raised portions or flanges along the two edges of such a belt, which raised edge portions are of an improved construction by which greater safety and increased durability 10 are attained.

A further object is to provide a construction by which supplementary contact or wearing portions are provided for the belt, greatly prolonging the life thereof under certain 15 operating conditions.

My improved construction also stiffens the belt so that it is better adapted to resist sagging between its supports, while at the same time the necessary flexibility of the belt is 20 maintained.

My invention further relates to arrangements and combinations of parts which will be hereinafter described and more particularly pointed out in the appended claims.

25 A preferred form of the invention is shown in the drawings in which

Fig. 1 is a plan view of a portion of my improved belt;

Fig. 2 is a partial end elevation thereof, 30 looking in the direction of the arrow 2 in Fig. 1;

Fig. 3 is a bottom view of the edge portion, looking in the direction of the arrow 3 in Fig. 2; and

35 Figs. 4, 5 and 6 are views similar to Fig. 2 but showing certain modifications.

Referring particularly to Figs. 1, 2 and 3, I have shown a portion of a wire conveyer belt formed of a plurality of spiral wire members 40 10, each member being interlaced with its adjacent members on each side thereof to build up a wire mesh fabric.

Re-enforcing or spreader rods 12 are preferably inserted between the coils of certain 45 adjacent spiral wires 10, and are shown in the drawings as inserted between the members of each successive pair of spiral wires. It will be understood, however, that more or less of the rods 12 may be used as required in 50 particular cases.

The spiral wires 10 and spreader rods 12, after assembly, have their end portions bent upward, as indicated in Fig. 2, to form edge flange portions 20, adapted to retain the transported material upon the belt and to prevent lateral displacement thereof. 55

The ends of the wires 10 are then bent reversely downward to form outer or double fold portions 22, but the spreader rods 12 preferably do not extend into these outer or 60 double fold portions.

While the belt is in its flat condition, the ends 24 of the members 10 are preferably twisted or looped together, as indicated in Fig. 3, to provide a rough form of selvage for 65 the fabric. After the edges are double-folded to the form shown in Fig. 2, these end portions 24 are positioned at the extreme lower edges of the outer folds 22, where any roughness or irregularity thereof will be 70 harmless. All of the spiral wires are continuous around the U-shaped reverse folds of the fabric and there is nothing exposed which can injure the operator.

These double folded edges greatly stiffen 75 the belt against sagging between supports but this stiffening is accomplished without destroying the desired flexibility of the belt. It will also be noted that the flexing of the belt tends to press the looped end portions 24 closer together, rather than tending to separate these end portions, as might be the case with up-standing flanges of single thickness. 80

In Fig. 4 I have indicated a slight modification in which the double or second folds 30 are disposed inside of the flanges 32, rather than outside as indicated in Fig. 2. This construction presents smoother outer surfaces and may be of advantage in special circumstances. 85

In Fig. 5 I have indicated a further modification in which the outer double folds 40 are extended downward and under the main body of the belt, as indicated at 42, thus providing supplemental wearing surfaces which greatly prolong the life of the belt, in installations where the belt is dragged along a stationary supporting surface 44 such as 90 the hearth of a furnace. 95 100

In the modification shown in Fig. 6, a belt formed as indicated in Fig. 2 is used in an inverted position, and shoes 50 are clamped on the downwardly extending double folded edges, providing wearing surfaces better adapted to resist hard wear than the coils of the spiral wire members. Obviously the shoes 50 may be removed and renewed, thus indefinitely prolonging the life of the belt.

Having described several forms of my invention, the advantages thereof will be readily apparent. When the belt runs between edge guides 60, as indicated in Fig. 2, the outer fold 22 takes the entire wear against the guide and even when this outer fold is entirely worn away, the up-standing edge portion 20 still remains in condition for continued use.

It is also found that a belt having my improved double re-enforced edges is so strengthened thereby that it may be run in vertical edge position instead of in the usual horizontal position. The double folded edge is well adapted to sustain the weight and wear on the belt when running in such vertical edge position, which is sometimes desirable for transporting articles which may be loaded by inserting them between the meshes of the fabric.

While the use of the spreader rods 12 is desirable, many of the advantages of my invention can be utilized when the spreader rods are omitted. These rods serve the particular function of preventing lateral shrinkage of the belt when under severe service conditions.

Having thus described my invention and the advantages thereof, I do not wish to be limited to the details herein disclosed, otherwise than as set forth in the claims, but what I claim is:—

1. A wire conveyer belt comprising interlaced spiral wire members extending transversely of the belt, the end portions of said spiral members being bent at an abrupt angle to the body of the belt to form longitudinally extended edge flanges projecting outwardly from the body of the belt and extending away from said body portion at a substantial angle and the extreme edge portions of said flanges being reversely folded to provide spiral wire flanges of double thickness and with said spiral members continuous across the body of the belt and around the double folded edges thereof.

2. The combination in a wire conveyer belt as set forth in claim 1, in which spreader rods are provided, extending transversely of said belt, each rod being engaged on opposite sides thereof by the coils of two adjacent spiral members, and the end portions of said rods being bent with said upstanding flange portions at predetermined angles to the body of the belt.

3. The combination in a wire conveyer belt as set forth in claim 1, in which said reversely folded edge portions are disposed outside of said flange portions to provide outer wearing surfaces therefor.

4. The combination in a wire conveyer belt as set forth in claim 1, in which said reversely folded portions are disposed outside of said flanged portions and extend under the sides of the body portion to provide supplemental wearing surfaces therefor.

5. The combination in a wire conveyer belt as set forth in claim 1, in which the ends of the spiral members are looped together at the edges of said reversely folded portions of said belt.

6. The combination in a wire conveyer belt as set forth in claim 1, in which wearing shoes are secured about the folded edges of said double flanges.

In testimony whereof I have hereunto affixed my signature.

FRANCIS N. WOODMAN.
